UNITED STATES PATENT OFFICE.

CHARLES I. MINKOFF, OF NEW YORK, N. Y.

TAG.

1,403,338.

Specification of Letters Patent. Patented Jan. 10, 1922.

Application filed October 7, 1921. Serial No. 506,064.

To all whom it may concern:

Be it known that I, CHARLES I. MINKOFF, a citizen of the United States, and resident of the city of New York, borough of Manhattan, county of New York, and State of New York, have invented a new and Improved Tag, of which the following is a full, clear, and exact description.

My invention relates to a tag, and aims 10 to provide certain new and useful improvements in connection with a device of this character.

In connection with the retail clothing trade and more particularly the dress department, which carry large sizes of dresses, 15 it is a well appreciated fact that considerable difficulty has been experienced, due to the somewhat slovenly appearance which a dress of this type has upon a conventional 20 clothes hanger.

Thus where a relatively large dress or similar article of clothing is to remain upon a hanger, the same appears to be, at first glance, far larger than the said dress actually is. Due to this objection it is often 25 time impossible to induce a prospective customer to try the same on, despite the fact that when this dress would be in applied position, the same would present an extremely neat appearance and would often 30 make the figure of the wearer appear far more slender than was actually the case.

Thus my present invention aims to provide a device which is adapted to be associated with the garment while the same is upon the hanger, so that the dress will 35 present a neat and slender appearance even while in this position, thus overcoming the difficulty aforementioned.

Still a further object of this invention is 40 the construction of a device of the character stated which may be manufactured at an extremely nominal figure, and which may also serve other purposes, in addition 45 to that afore specified, in that it may act as a price tag, size tag, etc.

Still further objects of this invention will 50 appear in the annexed specification, taken in connection with the drawings, which latter 55 illustrate one practical embodiment of my invention, and in which;

Figure 1 is a front view of a garment with my improved tag associated therewith.

Figure 2 is a rear view of the same.

Figure 3 is a sectional plan view taken

along the line 3—3 and in the direction of the arrows indicated in Figure 2, and Figure 4 is a face view of the tag.

In these views the reference numeral 5 indicates the body of a garment of any desirable character which, as is customary, is provided with a belt 6, and is supported upon a conventional hanger 7.

As has been clearly indicated in Figure 3 however, I provide tacks 8 in the belt 6, 65 which serve to properly retain the said belt with respect to the garment. It is to be noted in this connection that these tacks are provided at points well spaced from each other, and are in fact preferably 70 formed adjacent the side edges of the garment so that when the tacked portions are drawn together, as in Figures 2 and 3, the back 9 of the garment will fall into folds.

Now to retain the garment in the position 75 indicated I conveniently utilize a tag of the construction shown in Figure 4. It will be seen that this element includes a body 10 having upwardly extending slits 11 in its lower edges, the said body being capable of 80 receiving a certain printing 12 so that it may serve a double purpose. As in Figures 2 and 3 the legs or end portions of the tag, i. e. those parts of the same beyond the slit 11, are adapted to extend into the space 85 extending between the belt 6 and body 5 of the garment at points beyond the tacks 8.

Thus the parts are retained in the position indicated, and it will be seen that the body of the garment is constricted by this 90 disposition of the parts so that the same falls into natural lines, and will not present an extremely baggy appearance which is so objectionable, the folds in the back 9 serving 95 to compensate for the depth which exists when the body of a wearer is within the garment.

If a customer desires to try a garment on it will be obvious that it will be but the work of an instant to remove the tag from 100 the position indicated so that this fitting may be accomplished, and thus all of the objects specified in the preamble of this specification has been accomplished, and it will be understood that numerous modifications of structure might readily be resorted to without in the least departing from the spirit of my invention, which I claim as:

1. In combination with a garment and belt having certain parts secured to said 110

garment, at points well spaced from each other, of means adapted to be associated with said belt, adjacent said points of attachment for constricting said belt.

5. 2. In combination with a garment, a belt and tacked portions well spaced from each other and serving to attach said belt to said

garment, of a tag, and legs forming a part of said tag, said legs being adapted to extend between said belt and garment and 10 having their inner edges engaging said tacked portions.

CHARLES I. MINKOFF.
